PNEUMATIC SPIRAL WATER PUMP

Filed March 21, 1929

Inventor

Thomas Westgard

By Watson E. Coleman
Attorney

UNITED STATES PATENT OFFICE

THOMAS WESTGARD, OF GREAT FALLS, MONTANA

PNEUMATIC SPIRAL WATER PUMP

Application filed March 21, 1929. Serial No. 348,966.

This invention relates to the class of pumps and particularly to an air lift pump.

The primary object of the present invention is to provide a pump adapted to be placed at the lower end of a well casing, which will draw into the casing and lift the liquid in which the pump is placed by means of a series of jets of air injected into and upwardly in the lower portion of the pipe 5 casing.

A further object of the invention is to provide a pumping device employing air jets for creating a suction and forcing the pumped liquid through the casing, employing in addition a spiral element which will act to impart a whirling motion to the air currents and to the water or liquid acted upon by which means a rapid and smooth flow of the liquid will be obtained.

The invention broadly contemplates the provision of a casing through the central portion of which a pipe section constituting a portion of a pump casing passes, this section being provided with a series of apertures each of which leads to an upwardly directed jet pipe located therein.

The first mentioned casing has connected therewith a compressed air line from which air under pressure is introduced into the casing from where it passes through the jet pipes into and upwardly in the pipe section referred to. The lower end of the pipe section is provided with the usual type of intake strainer and in its upper portion there is arranged an elongated spiral fin which acts to impart a rotary motion to the liquid forced through the pipe by the discharge of air through the jets therein.

The invention will be best understood from a consideration of the following detailed description taken in connection with the accompanying drawing forming a part of the present invention with the understanding, however, that the invention is not confined to any strict conformity with the showing of

the drawing but may be changed or modified so long as such changes or modifications mark no material departure from the salient features of the invention as expressed in the appended claims.

In the drawings:

Figure 1 is a longitudinal sectional view of the water pump embodying the present invention;

Figure 2 is a sectional view through the coupling between one of the jet pipes and the intake pipe of the pump;

Figure 3 is a sectional view taken upon the line 3—3 of Figure 1;

Figure 4 is a detailed view of a modified form of fin mounting.

Referring to the drawings in detail, it will be seen that the pneumatic spiral water pump embodying this invention consists of a compressed air casing indicated generally by the numeral 1, which casing is formed of a pipe section capped at the upper and lower ends by the reducing couplings 2 and 3 respectively, the coupling 2 having secured to and opening through the wall thereof the laterally extending nipple 4 to which a compressed air pipe line 5 may be attached.

Passing centrally through the compressed air casing 1 is a liquid intake pipe, 6, the upper and lower ends of which are threaded- 75 ly connected as indicated at 7 with the smaller ends of the reducing couplings 2 and 3 in the manner shown, the upper end of the water intake pipe extending through the coupling and projecting a slight distance there- 70 above as indicated at 8.

The intake pipe 6 is provided with a series of apertures 9 disposed both circumferentially and longitudinally thereabout in each of which the right angularly directed lower 85 end 10 of an air jet pipe or nozzle 11 is secured, each of these nozzles being arranged within the intake pipe and directed upwardly therein as shown. The outer end of the angled portion 10 of each air jet pipe where 90

it extends through the aperture 9 in which it is placed has threaded thereon a locking nut 12 which maintains the pipe in set position.

5 Secured to the lower end of the compressed air chamber is a water screen or cage 13 of the usual type into which the lower end of the intake pipe 6 opens.

In the upper portion of the intake pipe 6, that is, the portion 8 which extends above the upper reducing coupling 2, there is secured an elongated spiraled fin 14 which consists of a strip of relatively thin metal torsionally twisted and secured at its edges to 15 the wall of the pipe in which it is placed. The upper end of the intake pipe 6 is suitably threaded as indicated at 15 to facilitate the application thereto of one of a number of pipe sections which make up a wall casing 20 and upon the lower end of which the present pump is designed to be mounted.

The compressed air line 5 may be provided with a suitable control valve such as that indicated at 16 so that the introduction of air 25 into the compressed air chamber may be regulated at will.

From the foregoing description it will be understood that by introducing air under pressure into the water intake pipe section 30 through the upwardly directed jets therein, a reduced pressure will be created about the intake screen, thus causing water surrounding the same to enter and pass upwardly through the pipe 6. As the column of water 35 ascends through the pipe 6 and the pipe casing attached to the upper end thereof, a rotary motion will be imparted thereto by the spiral fin 14, which action will tend to further increase the reduced air pressure or 40 condition of partial vacuum in the lower end of the pipe and cause the water to pass upwardly faster and smoother.

While the length of the spiral fin 14 may be of any number of inches desired, it is preferred that when using the same in a pipe 45 of two and one-half inches diameter that a three-quarter twist or turn be given thereto for each eighteen inches of length.

While in the foregoing, I have described 50 the spiral as being secured in the upper end of the water intake pipe 6, it is apparent, of course, that if desired this spiral may be made a part of a separate pipe section or nipple such as that shown in Figure 4 and indicated 55 by the numeral 17. When the spiral is provided in this manner the nipple may be readily applied or removed from the upper end of the pipe section 6 and the lower section of the pipe line to which the pump is attached 60 will then receive the spiral 18 carried by the nipple and will be attached to the upper end of the nipple as will be readily understood.

I claim:

1. A pneumatic pump comprising a cylindrical body designed to be secured at the

lower end of a well pipe line and open for the intake of fluid thereinto, a plurality of jet tubes within and directed upwardly in the body, means for introducing air under pressure to each of said jet pipes for discharge 70 therethrough into the body, and spiral means within the upper portion of said body and positioned at the lower end thereof between a plurality of jet pipes for imparting a spiral motion to the fluids passing therethrough, 75 said jet pipes opening through the wall of the body and disposed longitudinally and circumferentially thereof and discharging air upwardly against said spiral means.

2. A pneumatic pump comprising a tubular body open at each end and adapted to have one end secured to the lower end of a pump line pipe, a plurality of air jet tubes disposed with the body at different elevations and directed upwardly therein, each of said jet tubes at its lower end opening laterally through the body wall, means for introducing air under pressure to each of said jet tubes, and spiral means within the body and having the lower end thereof extended downwardly of the upper ends of the upper of said jet tubes for imparting a spiral motion to fluids passing therethrough said jets discharging air upwardly against said spiral means. 90

3. A pneumatic pump comprising a tubular body open at each end and adapted to have one end secured to the lower end of a pump line pipe, a plurality of air jet tubes disposed with the body at different elevations and directed upwardly therein, spiral means positioned between the upper of said jet tubes, each of said jet tubes at its lower end opening laterally through the body wall, a compressed air casing enclosing that portion 100 of the body having the jet tubes opening therethrough, and means for conducting air to the casing. 95

4. A pneumatic pump comprising a tubular body open at each end and adapted to have one end secured to the lower end of a pump line pipe, a plurality of air jet tubes disposed with the body at different elevations and directed upwardly therein, each of said jet tubes at its lower end opening laterally through the body wall, a compressed air casing enclosing that portion of the body having the jet tubes opening therethrough, means for conducting air to the casing, and a spiral element positioned within the body 110 and mounted at the lower end thereof between a pair of said jet tubes designed to impart a whirling motion to fluids passing therethrough. 115

5. A pneumatic pump comprising a tubular body open at each end and adapted to have one end secured to the lower end of a pump line pipe, a plurality of air jet tubes disposed with the body at different elevations and directed upwardly therein, each of said 120 125 130

jet tubes at its lower end opening laterally through the body wall, a compressed air casing enclosing that portion of the body having the jet tubes opening therethrough, means for conducting air to the casing, a spiral element positioned within the body designed to impart a whirling action to fluid passing therethrough and mounted at the lower end thereof between the upper of said jet tubes, and
10 a strainer element carried upon the lower end of the cylindrical body.

In testimony whereof I hereunto affix my signature.

THOMAS WESTGARD.
